UNITED STATES PATENT OFFICE.

WILLIAM G. ANDERSON, OF BOSTON, MASSACHUSETTS, ASSIGNOR OF ONE-HALF TO WILLIAM L. ANDERSON, OF SAME PLACE.

WEATHER-STRIP.

SPECIFICATION forming part of Letters Patent No. 343,656, dated June 15, 1886.

Application filed October 29, 1885. Serial No. 131,317. (No model.)

To all whom it may concern:

Be it known that I, WILLIAM G. ANDERSON, of Boston, in the county of Suffolk and State of Massachusetts, have invented a new and useful Improvement in Weather-Strips, of which the following, taken in connection with the accompanying drawings, is a specification.

My invention relates to the production and use of a new material for forming that part of a weather-strip that is yielding—that is, the part that forms the packing—the object being to produce a fabric one side of which is soft and yielding, while the other side—that is, the side inclosed and most liable to be injured by moisture—is coated with a water-proof substance, the whole being cheap and easily applied to the holding or foundation strip or bead. I attain this object by the mechanism shown in the accompanying drawings.

Figure 1 is a perspective view showing my improved fabric applied to a form of molding used for doors. Fig. 2 is a vertical section, taken centrally, of an ordinary window parting-bead, the upper end being shown in perspective. Fig. 3 is a longitudinal section with the improved fabric applied. Fig. 4 is a cross-section of a parting-bead with my fabric applied, and Fig. 5 is a cross-section showing a modification of my invention to be applied to such as may require considerable compression and expansion.

In the drawings, C represents a strip of felt, and D a coating of rubber applied to it. This compound strip of felt and rubber forms a material that is at once very yielding, flexible, and water-proof, so that it cannot absorb moisture, and thus become liable to rot by dampness, nor break or crack from freezing. By this device—that is, using a com-

pound fabric of felt and rubber—I attain all of the good qualities of rubber and of felt and avoid the disadvantages incidental to either of these materials when used alone, as has heretofore been the practice.

In Figs. 1 and 2 I have shown my invention as embodied in a door-strip, C D being the rubber-felt strip inserted in the groove E, made in the wood molding A, and therein secured by any desirable means.

In Figs. 3 and 4 I have shown my invention as embodied in a parting-bead, and in Fig. 5 a modification for use on doors, or at such places as may require considerable elasticity and range.

In the modification I use a soft-rubber tube, H, which lies next to the molding K and serves as a preventative of the accumulation of moisture inside of the felt, and also as a cushion to add to the elasticity and range of compression of the strip.

I am aware of the patent to J. W. Brown, No. 143,324, dated September 30, 1873, subject "Carpentry," and I do not wish to claim anything that is shown or described in that case.

I claim—

In weather-strips, parting-beads, and closing-moldings, the combination of the molding or base-piece with a lining of felt, said felt being treated to a coat of soft rubber, whereby a flexible yielding, elastic, adhesive, and water-proof lining is produced, having one side smooth, water-proof, and adhesive, while the other side retains its felty nature, and the whole is soft and pliable, all substantially as described, and for the purpose set forth.

WILLIAM G. ANDERSON.
